UNITED STATES PATENT OFFICE.

CARL J. LAMB, OF PHILADELPHIA, PENNSYLVANIA, ASSIGNOR TO WESTINGHOUSE ELECTRIC AND MANUFACTURING COMPANY, A CORPORATION OF PENNSYLVANIA.

TURBINE-COOLING MEANS.

Application filed November 4, 1925. Serial No. 66,831.

My invention relates to elastic fluid turbines, more particularly to means for effecting an even distribution of heat in the rotors thereof when idle, and has for its object the provision of apparatus of the character designated which shall effectively prevent an uneven distribution of heat throughout the mass of an idle turbine rotor.

Apparatus embodying features of my invention is illustrated in the accompanying drawing forming a part of this specification, in which the single figure is a sectional view of a turbine having my improved apparatus applied thereto.

In the operation of power plants, as is well known, there is ordinarily a variation of power demand in a day's operation. During certain hours of the day more power units must be put in service to supply the power demand than during other hours. It follows therefore that in a day's operation one or more units are operated for a part time only and are shut down the other part of the time.

Where elastic fluid turbines are employed as prime movers under the circumstances mentioned, difficulties have been encountered due to the unequal distribution of heat within the turbine casing during idle periods.

When the turbine is in operation, its rotor or portions thereof, assume the temperature of the motive fluid, which may be upwards of 700° F. When the turbine is shut down and remains idle for several hours the temperature within the casing becomes higher at the top than at the bottom and the idle rotor cools off to a greater extent at the bottom than at the top. The lower part of the rotor being cooler than the upper part,

it contracts to a greater degree so that the rotor is caused to bow or bend upwardly due to the differences in temperature. If now the turbine is again started it will be found to be decidedly out of balance and rubbing of the parts is liable to occur if it is brought up to its designed speed before the heat of the rotor has again become evenly distributed throughout its mass.

Various expedients have been resorted to in order to overcome the before-mentioned difficulty; that most commonly employed being the provision of a separate motor with suitable gearing to keep the rotor of the idle turbine slowly rotating during its idle pe-

riods. This and other expedients known to me are obviously expensive and cumbersome.

Another deleterious effect on the turbine which has been found to follow intermittent periods of operation is that considerable condensation occurs within the casing during idle periods. Inasmuch as this condensation takes place in the presence of air, serious corrosion of the turbine passages and blading follows, particularly when formed of iron or steel, entailing overhauling and reblanding before it would otherwise be necessary.

In my application, Serial Number 37,732, filed June 17, 1925, entitled Turbine cooling means and assigned to the Westinghouse Electric & Manufacturing Company, there is disclosed a means for establishing and maintaining a circulation of air through the casing of an idle turbine in such a way as to bring about an evenly distributed cooling of the turbine rotor. While the method therein disclosed has proven eminently satisfactory in service, I have found that the same result may be more quickly obtained by introducing air under a relatively high pressure into the casing of an idle turbine, maintaining the pressure therein at a relatively high value, and permitting circulation of the air therethrough by natural leakage through the glands and the air discharging apparatus of the condenser, where the turbine is running condensing. The air, which is provided under from 4 to 7 atmospheres of pressure, has the quality of conveying heat more rapidly away from the rotor than where atmospheric pressure is employed and the cooling of the rotor is thus more effectually done.

Referring to the drawing for a better understanding of my invention, I show a turbine having a casing 10 and a rotor 11. Motive fluid for normally driving the turbine is admitted thereto through an inlet 12 and is exhausted therefrom into a condenser 13. In order to prevent leakage along the turbine shaft into or out of the turbine casing when running there are provided at the ends of the rotor, sealing glands 14 and 16 respectively. The sealing glands are of a well known type which operate by reason of centrifugal force acting on a body of liquid to produce a sealing annulus therearound and are not here described in detail.

It is understood, however, that the sealing quality of this type of gland depends upon the turbine being in operation and during idle periods a leakage of fluid is permitted therethrough.

Included in the condenser 13 is a baffle 17 under which the air and non-condensable vapors coming from the turbine pass and travel upwardly to an air off-take 18. Connected 10 to the air off-take 18 is an ejector 19 which operates, when the turbine is in operation, to eject the air and non-condensable vapors from the condenser. During idle periods, should there be pressure of air within the 15 condenser 13 it is free to pass outwardly through the ejector throat 20.

At 21 is shown a conduit which connects with a suitable source of air under pressure, not shown, but which may be from the air 20 pressure source commonly maintained in power plants. The conduit 21 is connected to the upper part of the turbine casing at 22 and serves to admit air under a relatively high pressure into the casing for the purpose 25 of cooling the rotor. A valve 23 is provided in the conduit 21 for the purpose of controlling the flow of air through the turbine casing. The conduit 21 should be of such size as to admit a sufficient quantity of air to the 30 casing to permit its being maintained at a relatively high pressure against the natural leakage through the turbine glands and the throat of the ejector.

Inasmuch as dense air under a relatively 35 high pressure has the quality of conveying heat away very rapidly, the rotor is quickly cooled and the pressure does not have to be maintained within the casing for any great period of time. It should further be pointed 40 out that the conduit 21 is preferably connected to the upper part of the turbine casing in order that the cooling effect take place in opposition to the natural flow of heat around the rotor, that is from the bottom 45 upwardly.

From the foregoing description the operation of apparatus made in accordance with my invention will be apparent. When the turbine is stopped after being in operation, 50 and the rotor is at approximately the temperature of the motive fluid, the valve 23 in the conduit 21 is opened a sufficient amount to admit a relatively large volume of air under 4 to 7 atmospheres of pressure into the 55 turbine casing and to maintain the pressure of the air at a relatively high value against the natural leakage through the glands 14 and 16 and the air off-take 18. Inasmuch as part of the air under pressure passes 60 through the glands 14 to 16 its greater cooling effect is distributed over the upper part of the mass of the turbine rotor. A portion of the air flows downwardly around the turbine rotor out through the exhaust into 65 the condenser 13 and from thence out

through the air off-take 18 and restricted throat 20, exerting a cooling effect around the entire periphery of the rotor. I have found that the dense air under a relatively high pressure effects a quick cooling of the 70 turbine rotor and effectually prevents an unbalanced distortion of the rotor taking place when starting.

From the foregoing it will be apparent that I have devised an improved turbine 75 cooling means capable of quickly and effectually providing an even distribution of heat throughout the mass of the turbine rotor during intermittently idle periods.

While I have shown my invention in but 80 one form, it will be obvious to those skilled in the art that it is not so limited, but is susceptible of various other changes and modifications, without departing from the spirit thereof, and I desire, therefore, that 85 only such limitations shall be placed thereupon as are imposed by the prior art or as are specifically set forth in the appended claims.

What I claim is:—

1. In a turbine, the combination of a casing, a rotor having a shaft and mounted within the casing, fluid pressure sealing glands for preventing the flow of elastic fluid to or from the interior of the casing 95 when running, said glands permitting said flow when the turbine is idle, and means supplying air under pressure into the interior of the casing when the turbine is idle for cooling the rotor, whereby air circulates 100 through the turbine and leaks outwardly through the glands.

2. In a turbine, the combination of a casing, a rotor having a shaft and mounted within the casing, fluid pressure sealing 105 glands for preventing the flow of elastic fluid to or from the interior of the casing when running, said glands permitting said flow when the turbine is idle, a condenser for the turbine, an air off-take for the condenser, 110 and means for introducing air under pressure into the interior of the turbine, whereby said air circulates through the turbine and outwardly through the air off-take.

3. In a turbine, the combination of a casing, a rotor having a shaft and mounted within the casing, a condenser for the turbine, an air off-take from the condenser, and means for introducing air under pressure into the interior of the turbine in the upper 120 part of the casing whereby said air circulates through the turbine and outwardly through the air off-take.

4. In a turbine, the combination of a casing, a rotor having a shaft and mounted 125 within the casing, a condenser for the turbine and arranged below the turbine casing, an air off-take for the condenser, and means for introducing air under pressure into the interior of the turbine, whereby said air 130

circulates through the turbine and downwardly and outwardly through the air off-take.

5. The method of maintaining an even distribution of heat throughout the mass of a turbine rotor during intermittently idle periods comprising introducing air under a relatively high pressure into the turbine casing, maintaining the air under a relatively high pressure therein, and permitting the leakage of air from the casing through the turbine glands.

10. The method of maintaining an even distribution of heat throughout the mass of a turbine rotor during intermittently idle periods comprising introducing air under a relatively high pressure into the turbine casing, maintaining the air under a relatively high pressure therein, and permitting the leakage of air from the casing through the turbine glands and air discharge apparatus of the condenser.

15. The method of maintaining an even distribution of heat throughout the mass of a turbine rotor during intermittently idle periods comprising introducing air under a relatively high pressure into the turbine casing, maintaining the air under a relatively high pressure therein, and permitting the leakage of air from the casing through the turbine glands and air discharge apparatus of the condenser.

turbine casing, maintaining the air under a relatively high pressure therein, and permitting the leakage of air from the casing 30 through the turbine glands.

20. The method of maintaining an even distribution of heat throughout the mass of a turbine rotor during intermittently idle periods comprising introducing air under a relatively high pressure into the turbine casing, maintaining the air under a relatively high pressure therein, and permitting the leakage of air from the casing through the air discharge apparatus of the condenser. 40

25. The method of maintaining an even distribution of heat throughout the mass of a turbine rotor during intermittently idle periods comprising introducing air under a relatively high pressure into the turbine casing, maintaining the air under a relatively high pressure therein, and permitting the leakage of air from the casing through the turbine glands and air discharge apparatus 45 of the condenser. 50

In testimony whereof, I have hereunto subscribed my name this twenty-ninth day of October, 1925.

CARL J. LAMB.
